VEHICLE IDENTIFICATION SIGN OR
SIMILAR ARTICLE

Charles L. Avery and John H. Cleave, both of
6150 Reseda Blvd., Apt. 102, Reseda, Calif.

Filed Nov. 20, 1964, Ser. No. 82,710

Term of patent 14 years

(Cl. D1—12)

FIG. 2

FIG. 3

FIG. 1

FIG. 4

FIG. 5

FIGURE 1 is a perspective view of a vehicle identification sign or similar article, showing our new design;

FIGURE 2 is an elevational view of one side;

FIGURE 3 is an elevational view of the other side;

FIGURE 4 is an end elevational view taken from the left side of FIGURE 3; and

FIGURE 5 is a bottom plan view taken from the bottom of FIGURE 2.

The dominant features of the design reside in the portions shown in full lines.

We claim:

The ornamental design for a vehicle identification sign or similar article, substantially as shown and described.
